Attorney

UNITED STATES PATENT OFFICE.

BERNARD JAKEWAY, OF HARRISON, MICHIGAN.

TRACE.

1,231,547.

Specification of Letters Patent. Patented June 26, 1917.

Application filed October 28, 1916. Serial No. 128,278.

To all whom it may concern:

Be it known that I, BERNARD JAKEWAY, a citizen of the United States, residing at Harrison, in the county of Clare and State of Michigan, have invented certain new and useful Improvements in Traces, of which the following is a specification, reference being had to the accompanying drawings.

This invention relates to harness and particularly to the traces thereof. The general object of my invention is to form a harness trace which shall be light, strong and comfortable to the draft animal.

A further object is as far as possible to do away with the use of leather or a combination of leather and iron and form the trace of metal alone.

A further object is to provide a trace so connected to the hame that it cannot become accidentally unhooked and so construct the eye which connects the trace to the hip strap that there will be no danger of the tail of the horse being caught in it.

Other objects will appear in the course of the following description.

My invention is illustrated in the accompanying drawings, wherein

Figure 1 is a perspective view of a trace constructed in accordance with my invention;

Fig. 2 is an elevation of the rear end of the trace showing the manner in which the slack of the chain may be taken up.

In the accompanying drawings, 10 designates a hame of any ordinary or usual construction and having the U-shaped eye 11. The trace proper comprises the longitudinally extending slightly curved metal rod 12, the ring 13, the straight metal rod 14 and the chain section 15. The rod 12 at its forward end is bent to form a hook 16 to engage with the U-bolt 11 and this hook is so formed that it can only be removed from its engagement with the U-bolt 11 by turning the trace at right angles to its normal position and shifting it laterally. This prevents any accidental unhooking of the trace from the hame which is a source of constant annoyance in other forms of traces known to me.

50 The rear end of the rod 12 is formed with an eye 17 which has loose engagement with the ring 13, and the rod 14 at its forward end is formed with an eye 18 which also has loose engagement with the ring 13. The belly band 19 engages with the ring 13 as does the back band 20. The ring 13 being a true

circle has no square corners for the straps 19 and 20 to work into. Where the connecting member 13 is rectangular the straps are very liable to work into the corners or 60 against the corners and to be cut off. By making the member 13 a true circle, the straps 19 and 20 work smoothly upon the ring and without the wear to which they are ordinarily subjected.

The rod 14 at its rear end is formed with an elongated eye 21 by bending the rod laterally and then extending the rod parallel to the rod 14 and then bending the extremity of this rebent portion inward against the rod 70 14 and welding it thereto at 22. The elongated eye provides for the connection of the hip strap 23 and permits the hip strap to work back and forth. If this strap were not permitted to work back and forth as described, the strap would chafe the horse. The length of chain 15 has its end link connected to the eye 21 and the rear link of the chain which is larger than the other links, or any of the links thereof may be connected 75 to the trace hooks 24 of the swingletree 25. In Fig. 2, I show a manner in which a slack of the chain may be taken up without leaving a large portion of the chain to hang loose. The rod 12 it will be seen is slightly curved 80 outward so that it will not rub the shoulders of the horse. I have found by experience that where a trace is constructed of smooth round iron there is much less friction against the flanks of the horse than where leather, 85 rope, or cable and chain are used. My improved trace is smooth and does not chafe and is as flexible as it is required to be. It cannot accidentally unhook from the hame, 90 will not wear the belly band and the back 95 band and permits the movement of the hip strap as stated.

The hook 16 has its bill extending parallel to the shank of the hook, which shank extends at an angle to the rod 12 as shown 100 clearly in Fig. 1. The curve or angle of this shank relative to the rod 12 keeps the hook from pushing ahead as this angular portion comes against the U-bolt. The hame and trace have to be turned relatively half way 105 around or the trace pulled out straight sideways before the hook can be disengaged from the hame.

Having described my invention, what I claim is:

110 A trace comprising a rod constructed to swingingly engage a hame staple, the rod

being curved outwardly away from the hame and formed at its rear end with an eye, a ring passing loosely through the eye, and a rod section having an eye at its forward end 5 loosely engaged with said ring, said ring serving as a means of attachment for a back band and a belly band, the rear end of the rod section being formed with an elongated

loop, said loop being adapted to be slidably engaged by a hip strap.

In testimony whereof I hereunto affix my signature in the presence of two witnesses.

BERNARD JAKEWAY.

Witnesses:

FRED F. COSGROVE,
F. WEATHERHEAD.
